Primary Examiner—Martie Thompson*Attorney, Agent, or Firm*—Seed and Berry LLP**[57] CLAIM**

The ornamental design for a combined stamp pad and container, as shown and described.

DESCRIPTION

FIG. 1 is an isometric view of a combined stamp pad and container showing my new design;

FIG. 2 is a top plan view thereof;

FIG. 3 is an end elevational view thereof;

FIG. 4 is an end elevational view of the end not shown in FIG. 3;

FIG. 5 is a side elevational view, the opposite side being a mirror image thereof;

FIG. 6 is a bottom plan view thereof;

FIG. 7 is a cross-sectional view of the base portion taken lengthwise;

FIG. 8 is a top plan view of the base member shown separately for convenience of illustration with the foam pads in a separated position;

FIG. 9 is a top plan view of FIG. 8 with the foam pads in contact;

FIG. 10 is an isometric view of FIG. 8;

FIG. 11 is an isometric view of a second embodiment of the present invention, all other views being identical to FIG. 2 through 10, except for the transparency of the lid member; and,

FIG. 12 is an isometric view of a third embodiment of the present invention, all other views being identical to FIG. 2 through 10, except for the deletion of the depression on the lid member.
